S. B. SULLIVAN

FURRING AND FASTENING DEVICE

Filed Jan. 16, 1926

INVENTOR.
SARAH B. SULLIVAN
BY *Joseph B. Gardner*
ATTORNEY.

UNITED STATES PATENT OFFICE.

SARAH B. SULLIVAN, OF BERKELEY, CALIFORNIA.

FURRING AND FASTENING DEVICE.

Application filed January 16, 1926. Serial No. 81,639.

My invention relates to a device for positioning and securing plastering netting or the like, in spaced relation to the wall of a building. More particularly the device is of 5 the type comprising a spacing member which is slidably mounted on a fastening member and normally held to resist removal therefrom and is arranged to cooperate with a projection on the latter whereby the netting wire may be gripped and held between such projection and the spacer after the device has been driven into position.

An object of the invention is to provide the device with a spacing member which will 15 not spread or flatten on the wall when forced thereagainst and thus insures a uniform and predetermined spacing of the netting from the wall.

Another object is to provide the device 20 with a spacing member which will have a bearing surface of maximum area and smoothness whereby mutilation of the surface to which it is applied may be prevented.

A further object of the invention is to provide 25 a device of the character described with which plaster will readily become keyed when applied thereover.

A still further object of the invention is to provide the device with a spacing member which will interfere to a minimum extent with the direct keying of the plaster to 30 the netting.

The invention possesses other objects and features of advantage, some of which, with 35 the foregoing, will be set forth in the following description of the preferred form of my invention which is illustrated in the drawings accompanying and forming part of the specification. It is to be understood 40 that I do not limit myself to the showing made by the said drawings and description, as I may adopt variations of the preferred form within the scope of my invention as set forth in the claim.

45 Referring to said drawings:

Figure 1 is a perspective view of one embodiment of the device of my invention.

Figure 2 is a plan view of a blank used 50 in forming the spacing member of the device shown in Figure 1.

Figure 3 is a fragmentary sectional view of a wall showing devices operatively positioned thereon both before and after being driven to final position.

Figure 4 is a perspective view of another 55 embodiment of the device.

The operative application of most of the heretofore used devices of the class to which the present invention relates has presented certain difficulties which have prevented a more wide-spread use of such devices. Thus, it is desirable and customary to drive the fasteners to place with a single blow of a heavy hammer, but most of the before mentioned devices, if the hammer blow be the least bit excessive, have tended to flatten out or to be driven into the sheathing so that the netting has either been spaced too close to the wall or is unevenly spaced therefrom, thus making difficult the placing of a plaster coat on the netting such as will have a uniform thickness and smooth exterior surface. On the other hand, the fasteners having spacing portions so formed that they cannot be flattened or driven into the wall, have 70 usually prevented the keying of the plaster to the netting immediately adjacent their point of contact with the netting. In accordance with the present invention, however, a fastener spacing member is provided which will neither be flattened out or driven into a wall and which will at the same time present a minimum portion thereof against the netting.

The embodiment of my invention shown 85 in Figures 1 to 3 inclusive comprises a fastening unit 7 having a nail portion 8 provided with a point 9 at one end and a wire engaging head 11 at the other end. As here shown, the head 11 is of circular form and is relatively large so that it may engage one or more strands of a wire netting 12 between itself and a suitable spacing or furring member.

90 Since, as previously pointed out, it is desirable that the spacing member present a large base to the sheathing 13 and have a comparatively small contact with the netting 12, and, furthermore, at the same time be comparatively non-collapsible and indestructible, I provide a spacing member 14 in which is utilized the principle of the rigidity of the triangle. As here shown, the member 14 is formed as though of a piece of tubing of triangular section placed with its axis 95 parallel to the surface 16 of the wall and with one face 17 resting thereagainst. The face 17, it will be noted, is provided with a 100 105

perforation 19 arranged to receive the shank 18 of the nail 8 which also passes through a suitable opening 21 provided at the top edge or corner 22 of the member 14 and 5 against which the netting 12 is arranged to be held seated by the nail head 11.

As here shown, the member 14 is of unitary structure and is formed by a suitable bending to shape of a blank 23 having 10 parallel end edges 24 and 26. It will be noted that the perforation 19 is provided in the center portion of the blank which forms the face 17, and that the edges 24 and 26 are each provided with segmental 15 perforations, so that when the shank is positioned in the perforation 19 and the end portions 27 and 28 of the blank have been bent from the edges of the portion 7 to bring the outer edges thereof into juxtaposition, the opening 21 will be defined about 20 the nail shank by the segmental perforations and the edges 24 and 26 will together define the spacing member bearing edge or corner 22. To insure against undue 25 relative movement of the edges 24 and 26 before and during the positioning of the fastener, the portion 27 is preferably provided with tabs 29 which may be bent down over the edge of the portion 28 as herein shown, but 30 it will be particularly noted that when the nail head is in position to hold the netting against the corner 22 that, owing to their angular disposition, the spreading apart of the portions 27 and 28 will be prevented by 35 the head without need of the tabs 29. It will be further noted that the nail shank 18 is preferably of uniform section and should tightly fit in the perforation 19 so that the fastening member may be primarily posi-

tioned and held near the nail point when 40 the fastener unit is assembled, handling of the fastener as a unit thus being made possible. It will also be noted that the tabs 29 project above the corner 22 and are preferably so spaced apart that the nail head 45 when driven against the spacer will bear thereagainst to thereby imprison the netting between itself and the edges 24 and 26 without undue pressure on the netting strands.

In the embodiment shown in Figure 4, it 50 will be noted that the upper nail opening 21' is rectangular rather than circular, so that the nail may, if desired, be angularly disposed with respect to the top edge 22'. In 55 this manner, the nail may be primarily inserted to slant toward a portion of wire to be stretched and then straightened up as, or before, it is driven, to thereby stretch the wire.

I claim:

In a device of the character described, a spacing member comprising a triangular tube formed of a strip of sheet metal with the ends recessed and abutting at one of the 65 corners, a fastener comprising a pointed and headed shank passing through the said spacer recesses and the side opposite said corner, said side being adjacent the pointed end of the shank whereby it may lie against 70 the wall when the device is operatively disposed, and means incorporated with the spacer for holding the strip ends together.

In testimony whereof, I have hereunto set my hand at Oakland, California, this 75 12th day of January, 1926.

SARAH B. SULLIVAN.
